UNITED STATES PATENT OFFICE.

EDMA H. CURTIS, JR., OF NORWOOD, OHIO, ASSIGNOR TO THE NIVISON-WEISKOFF COMPANY, OF READING, OHIO, A CORPORATION OF OHIO.

MACHINE ELEMENT.

1,263,042.

Specification of Letters Patent. Patented Apr. 16, 1918.

Application filed March 6, 1917. Serial No. 152,462.

To all whom it may concern:

Be it known that I, EDMA H. CURTIS, Jr., a citizen of the United States, and a resident of Norwood, in the county of Hamilton and State of Ohio, have invented certain new and useful Improvements in Machine Elements, of which the following is a full, clear, and exact description, reference being had to the accompanying drawings, forming 10 part of this specification.

It frequently happens that a part or member, which is to be operated by a cam on a power shaft, is in such close proximity to the power shaft that only a short leverage is 15 possible, and if the work to be performed by such part or member is heavy, considerable power must be applied to the driving shaft which, when the usual form of cam is employed, must rotate slowly. The invention 20 described herein has for its object a construction whereby the efficiency of a large cam driven at a high speed can be had without increasing the distance between the driving and the driven parts. The invention is 25 hereinafter more fully described and claimed.

In the drawings,

Figure 1 is a view partly in section and partly in elevation of a machine of the type shown and described in Letters Patent No. 30 1,007,156, dated October 21, 1911, embodying my improvement.

Figs. 2 and 3 are side and edge elevations showing portions of my improved device on an enlarged scale.

Fig. 4 is a side elevation of another form of my invention.

In the machine shown in Fig. 1, it is desired to transmit motion from the power shaft 1 to one or more shafts as 2 or 3. One 40 or more sprocket wheels are keyed on the driving shaft and around these wheels are placed endless chains 5 and 6, which also pass partially around drums 7 and 8 loosely mounted on the shafts 2 and 3. These shafts 45 are provided with radially projecting arms 9 on opposite sides of the drums, the number of such arms being dependent upon the angular movement (e. g. 180, 120 or 90 degrees) to be imparted to the shafts 2 and 3. The extent to which the drums are encircled by the chains will also be dependent on the required angular movement of the shafts 2 and 3. The sprocket chains are provided with laterally projecting pins 10 adapted 55 to engage the arms 9 as the chains pass

around the shafts 2 and 3, and thereby impart the desired angular movement to the shafts. The number of projecting pins on the chains is dependent upon the desired frequency of movement of the driven shafts 60 during a complete traverse of the chains. It will be understood that such frequency of movement of the shafts is also dependent on the peripheral length of the chain. The same frequency can be had with a short 65 chain having one pin or a chain of double the length but having two equally spaced pins.

As the chains can be arranged around a plurality of guide pulleys 11, any desired 70 length of chain can be employed, thus permitting a large increase in the rate of rotation of the driving shaft 1 without increasing the periodicity of movements of the shafts 2 and 3. And further the movement 75 described herein permits of the transmission of power around parts of a machine lying between the power and driving shafts.

In order to prevent accidental movements of the shafts 2 and 3, provision is made for 80 locking the same after each movement. A suitable construction for this purpose consists of curved fingers 12 loosely mounted on shafts or pins 13 (which in this case carries one of the guide pulleys) and adapted to be so shifted by a spring 14 that teeth 15 on the fingers will be forced into notches 16 on the ends of the arms 9, as clearly shown in Fig. 2. In order to release the arms 9, cam surfaces 17 are so formed on 90 the fingers 12 that the pins 10 on the chains will traverse such surfaces just before engaging the arms 9 and so shift the fingers as to withdraw the teeth from the notches. In order that said tooth may not engage a 95 following arm until the movement has been completed, the arms are provided with rollers 18 which will engage the cam surfaces 17 and hold the fingers out of the path of movement of the arms until the latter have completed their movement and a notch 16 is in position to receive a tooth.

In the modification shown in Fig. 4, the power shaft 1 is shown as driving a shaft 20 situated alongside of it. The shaft has a 105 sprocket wheel controlling an endless chain 5 which passes around a drum 8 on the shaft 2, which drum has projecting arms 9, all as in the above description of the main exemplification of the invention illustrated. 110

The sprocket chain has a pin 10 adapted to engage the arms 9, 9, as the chain passes over the drum.

There is a finger 12, as above, which is mounted on a pin 21. A spring 22 mounted under a bracket arm 23 and operating on a pin 24 serves to pull down on the arm 25 which is connected to the finger member. The spring by pulling on the arm thereby holds the tooth 15 on the finger in the notch 16 in one of the arms 9 on the shaft drum.

The position of the fingers is such that it has not required that any particular cam surface, as at 17 above, need be provided, as the pins 10 on the chain merely contact with the extension 26 on the finger member. The rollers 18 on the arms 9 will also contact with this extension in the same manner as in the first example.

20 It will be readily understood that in case it is desired to vary the rate of rotation of the power shaft relative to the parts to be driven thereby, the length of the chains can be varied by inserting or removing links.

25 Only the portion of the chain passing from the driven to the driving shaft is in tension and the portion of the chain passing from the driving to the driven shaft may hang loosely, unless it becomes necessary to guide it around some other part of the machine.

30 The employment of endless chains to transmit motion from one shaft to another is quite common in the arts, but in all such cases the relation of the driving to the driven shaft is such that both are rotated simultaneously, and the extent of angular movement of the driven shaft and the periodicity of such angular movement is in no way dependent on the length of the sprocket chain.

35 It is also a known practice to impart intermittent rotation to a star wheel by means of bringing into engagement with its teeth a finger, said finger located fixedly on a driven element or on a chain or belt operated by the driven element. In these cases the chain does not pass around in star wheel, however, and it is readily appreciated that in such a mechanical device as that last mentioned, there has to be much special construction, chain or belt tensioning and the like.

40 So far as I am aware, it is entirely novel to transmit intermittent rotary motion from one element to another by means of an endless flexible member passing around each of them.

45 Having thus described my invention, what I claim as new and desire to secure by Letters Patent, is:—

1. In a mechanism for obtaining intermittent motion from continuous rotary motion by means of a flexible member, the combination of a driving shaft, a sprocket wheel thereon, a shaft to be driven, and an endless

sprocket chain of a length substantially greater than twice the distance between the axes of said shafts and in constant engagement with the driving shaft, and partially encircling the other shaft, and means for causing the sprocket chain to intermittently engage the shaft to be driven and impart a partial rotation thereto.

2. In a mechanism for transmitting rotary motion, the combination of a driving shaft, a sprocket wheel thereon, a shaft to be driven, an endless sprocket chain of a length substantially greater than twice the distance between the axes of said shafts and in constant engagement with the driving shaft, guiding means for the chain adapted to cause the chain to move partially around the shaft to be driven, and radial arms on the shaft to be driven to engage the chain while moving around the shaft.

3. In a mechanism for transmitting rotary motion, the combination of a driving shaft, a sprocket wheel thereon, a shaft to be driven, an endless chain of a length substantially greater than twice the distance between the said shafts and in constant engagement with the driving shaft, guiding means for the chain adapted to cause the chain to move partially around the shaft to be driven, and radial arms on the shaft to be driven adapted to engage the chain while moving around said shaft, and said arms adapted to release the shaft upon partial movement thereof.

4. In a mechanism for obtaining intermittent rotary motion from continuous rotary motion by means of a flexible connection, the combination with a continuous rotating element, and an element to be rotated thereby intermittently, of an endless flexible member passing around and driven by the continuous rotating element, said flexible element partially encircling the element to be driven, and means on the flexible element and the element to be driven to intermittently engage for transmitting such intermittent rotary motion.

5. In a mechanism for transmitting rotary motion, in combination with a driven rotating element, and an element to be rotated thereby intermittently, an endless flexible member passing around and driven by the driven rotating element, idler means on the element to be rotated intermittently to permit said flexible element to pass partially around said element without actuating it, and means operatively connected to said element adapted to be intermittently engaged by said flexible element for imparting such intermittent rotary motion to the element to be rotated.

EDWARD H. CURTIS, JR.
